UNITED STATES PATENT OFFICE.

GEORGE M. KNEUPER, OF NEW YORK, N. Y.

APPARATUS FOR MANUFACTURING FILTERS.

No. 825,274.

Specification of Letters Patent.

Patented July 3, 1906.

Original application filed August 12, 1904, Serial No. 220,450. Divided and this application filed May 16, 1906, Serial No. 260,676.

To all whom it may concern:

Be it known that I, GEORGE M. KNEUPER, a citizen of the United States, and a resident of the borough of Manhattan, city, county, and State of New York, have invented certain new and useful Improvements in Apparatus for Manufacturing Filters, of which the following is a specification.

My invention relates to apparatus for the manufacture of filters, and has for its object to provide a rapid and inexpensive means of making efficient filters.

The invention will be fully described hereinafter and the features of novelty pointed out in the appended claims.

The present application is a division of one filed by me in the United States Patent Office August 12, 1904, Serial No. 220,450.

Reference is to be had to the accompanying drawings, in which—

Figure 1 is a sectional elevation of an apparatus for making filters according to my invention, showing said apparatus at the initial stage of the operation. Fig. 2 is a similar view showing the apparatus at the final stage of the operation. Fig. 3 is a sectional plan on line 3 3 of Fig. 1. Fig. 4 is a longitudinal section of form of filter made with the apparatus shown in Figs. 1, 2, and 3. Fig. 5 is a sectional elevation of another form of filter-making apparatus constructed according to my invention. Fig. 6 is a sectional elevation of still another form of filter-making apparatus embodying my invention, and Fig. 7 is a sectional plan taken on line 7 7 of Fig. 6.

In making my improved filter I employ a vessel having a perforated wall, so that the liquid may pass therethrough, and adjacent to this perforated wall I locate an expansible body adapted to be forced toward said wall. If the vessel is filled with paper-pulp suspended in water and if then the expansible body is distended or blown up quickly, the water will be forced through the perforated wall, but the pulp will remain compressed between the expansible body and the perforated wall and will form a continuous sheet or lining against said wall. In detail the procedure may be as follows:

In Figs. 1, 2, and 3, A indicates the operative inner wall of the apparatus, which may be cylindrical and may consist of perforated sheet metal or of wire-netting. B is a pouch made of suitable porous or pervious material, such as canton-flannel. The upper edge of

this pouch is folded over the outer wall C, which, as shown, may consist of two connected wire screens of cylindrical shape. The outer wall C is secured to a bottom D, which 60 may be slotted or perforated. This bottom D is preferably provided with lugs D', so that the entire receptacle may be conveniently set within a tank E or the like. Within the perforated wall A is arranged an expansible 65 body F, for which purpose I generally employ a rubber bag. This bag extends substantially the entire length or height of the receptacle and is fastened at its top below a cover G. This cover G may be provided 70 with an opening for filling, which is closed by a plug G'. The said cover G is normally held down against a flange A' at the top of the inner wall A by means of a nut H, which screws upon a perforated tube I, extending 75 through the cover G and within the receptacle. To this tube I is secured the upper end of the bag F. The lower end of the tube may be free within the receptacle or, if preferred, the lower end of the tube may, as 80 shown, be passed through the rubber bag and through the bottom B, being secured thereby by a nut I'. A flange C' for strengthening is preferably located at the upper end of the outer wall.

In operation the above-described apparatus is placed in a tank, which is either empty or filled with water. Pulp suspended in water is poured into the central chamber J. Air is then blown into the tube I, so as to issue 90 through the perforations thereof into the bag F. By the application of suitable pressure the bag is quickly expanded against the inner wall A into substantially the form shown in Fig. 2. The water is quickly driven out 95 through the perforated walls A and C and the previous pouch B; but the pulp is retained against the inner surface of the inner wall A and forms a continuous compressed lining thereon. The pressure will of course cause 100 some of the pulp lining to enter into meshes of the wall A, and the said wall and its pulp lining will therefore be securely connected, so as to render them available for use as one structure. If desired, however, the lining 105 may be separated from the wall A and used alone. After the lining is formed on the inner wall, as described, the receptacle is removed from the tank. The compressed lining K produced on the perforated wall A constitutes an efficient filter, either alone or together, with said wall as a carrying-frame.

This filter, Fig. 4, may be removed from the apparatus by unscrewing nut H, removing the cover G, grasping the flange A' at the top of the inner wall and lifting the inner wall, together with the compressed-pulp lining K, from the receptacle. This inner wall with the compressed lining thereon may then be used as a filter in any suitable apparatus. It will be seen that one face of the lining engages the perforated wall A, the other face being freely exposed, so that the lining is permitted to expand in one direction in case it should swell while in use. I consider it preferable when using the filter to have the liquid pass in through the exposed inner surface of the lining and out through the meshes of the perforated wall. Another inner wall of like construction is then put in the receptacle, and a filter-lining is formed thereon in the same manner as above described, and thus the apparatus may be used for producing a great number of filters. It will be understood that after the receptacle has been removed from the tank and before the inner wall is removed the rubber bag should be deflated. It is not absolutely necessary to use the pouch B; but the use of said pouch prevents the fibers from passing to and through the outer wall C when the perforations of the inner wall are beyond a certain size. An easy separation of the inner wall A from the other parts of the apparatus is thus insured after the pulp lining has been made. The pouch B may be dispensed with if the meshes of the inner wall are sufficiently close. In any event, however, the top or cover G should be securely connected with the bottom D, so as to prevent any leakage at the edges of the inner wall A. A rubber gasket G² may be applied to the cover, so as to engage the flange A'. In order to provide a receptacle for the water expelled by the inflation of the bag F without making the tank E of unduly increased height, the latter may be made with a stand-pipe E', extending upwardly beyond the cover G.

It will be obvious that in the operation above described an opening K' will be produced at the bottom of the filter-lining K. (See Fig. 4.) In cases where it is desired to produce a filter having a closed bottom the pipe I² would terminate above the bottom D² of the receptacle and within the bag F', Fig. 5. In this case the cover G³ could be removed, together with the pipe I² and bag F', after the production of the filter, and then the bottom of the lining would be entirely closed by the end portion. As in this case the pipe I² does not extend through the bottom D², different means from those used in Figs. 1, 2, and 3 must be provided for holding down the cover G³. For instance, screw-rods L may be hinged to the bottom D² and fitted into slotted ears G⁴ of the cover, the tension being produced by means of winged nuts M.

In Figs. 6 and 7 the inner wall a is formed by rolling a sheet of wire-gauze or the like into cylindrical form, so that there will be two or more layers at certain points, and this cylinder is then held in shape in any suitable manner, as by end rings a', L-shaped in cross-section and adapted to engage gaskets d' and g², located, respectively, on the bottom d and cover g. The bottom d is shown integral with a cylindrical imperforate outer wall e, 75 which wall may be provided with a stand-pipe e', corresponding in function to the stand-pipe E'. A plug g' normally closes an opening in the cover g, through which the chamber J may be filled with water in which pulp is suspended. An expansible body f is also contained in this chamber, said expansible body f being fitted on the pipe i, through which air or other suitable medium may be blown or forced into the bag f to expand the same. Nuts h and i' secure the parts of the apparatus together. The operation is exactly the same as with the form of construction first described with the additional advantage that the pulp lining may be stripped 85 much more readily from the perforated wall upon which it is formed, so that such lining may be taken off and applied to other carriers. By this construction the cleaning of the perforated wall is also much facilitated. 90 While I have described the production of a compressed-pulp lining forming a filter on the inner surface of the inner wall, I desire it to be understood that my invention is not restricted to this construction and operation, 100 but that, generically speaking, I may force an impervious surface (represented in this case by the rubber bag F') toward one face of a perforated wall, (represented by the wall A-a,) whether such wall be cylindrical or of any other shape and whether the surface exerting pressure be located on the inside of the said wall or elsewhere. In each case the impervious surface moving toward the perforated wall forces the liquid through said wall and compresses the pulp into a continuous layer on one surface of said wall. 110

In all the forms herein shown it obviously is easy to substitute perforated walls A a of different diameters for those shown in the drawings, so that the same apparatus may be used for making filters of different sizes.

Instead of pulp I may employ any other substance which is capable of being suspended in water or other liquid and is further capable of being separated from said liquid by forcing the liquid through a perforated wall. If such substance is porous, the resulting sheet or lining may be used for filtering purposes. A lining will be produced in all events which conforms to the shape of the wall, so that my invention, considered broadly, provides means for molding articles of various kinds quickly and without requiring the application of heat. 130

Various modifications may be made without departing from the nature of my invention.

I claim as my invention—

- 5 1. An apparatus for making articles from substances suspended in liquids, comprising a receptacle having an open-ended perforated inner wall A, an expansible bag F within said inner wall, a pervious pouch B surrounding said inner wall and forming a bottom to the space embraced by said inner wall, a perforated open-ended outer wall C surrounding the body of the pouch and a solid bottom D to which the wall C is secured.
- 10 2. An apparatus for making articles from substances suspended in liquids, comprising a perforated inner wall, an imperforate outer receptacle or tank, an expansible body located within the perforated wall, and a stand-
- 15 pipe connected with the outer receptacle and extending above the top thereof to receive the surplus of liquid expelled by the expansion of the said body.
- 20 3. An apparatus for making articles from substances suspended in liquids, comprising

two perforated walls nested one within the other, and one capable of sliding into and out of the other, a pervious pouch located between said walls and forming a means for the convenient removal of the inner wall, 30 and an expansible body located within the inner wall.

4. An apparatus for making articles from substances suspended in liquids, comprising a perforated wall, an imperforate outer receptacle or tank within which said perforated wall is located, an expansible body located on one side of said perforated wall, and a stand-pipe connected with the tank on the other side of said perforated wall, and extending above the top of the tank to receive the excess of liquid expelled by the expansion of said body.

In testimony whereof I have hereunto set my hand in the presence of two subscribing 45 witnesses.

GEORGE M. KNEUPER.
